DESIGN FOR A PUMP

Herman M. Loeber, Beatrice, Nebr., assignor to Dempster Mill Manufacturing Company, a corporation of Nebraska

Application April 17, 1939, Serial No. 84,339

Term of patent 3½ years

To all whom it may concern:

Be it known that I, Herman M. Loeber, a citizen of the United States, residing at Beatrice, in the county of Gage and State of Nebraska, have invented a new, original, and ornamental Design for a Pump, of which the following is a specification, reference being had to the accompanying drawing, forming part thereof.

The figure is a view in perspective of a pump showing my new design.

The other side of the pump is substantially
like the side shown except that it has no spout
thereon.

I claim:

The ornamental design for a pump, as shown
and described.

HERMAN M. LOEBER.
